UNITED STATES PATENT OFFICE

106,143

DESIGN FOR A LOCOMOTIVE

Raymond G. F. Loewy, New York, N. Y., assignor
to The Pennsylvania Railroad Company, Phila-
delphia, Pa., a corporation of Pennsylvania

Application March 10, 1937, Serial No. 68,109

Term of patent 14 years

To all whom it may concern:

Be it known that I, Raymond G. F. Loewy, a citizen of the Republic of France, residing in the Borough of Manhattan, in the city, county, and State of New York, have invented a new, original, and ornamental Design for a Locomotive, of which the following is a specification, reference being had to the accompanying drawings, forming part thereof.

This application, to the extent that it includes matter shown in my pending application for Letters Patent, Serial No. D-63,911, filed July 17, 1936, is a continuation in part of said previously filed application.

Of the drawings herein:

Fig. I represents a perspective view, taken

from the front end of a locomotive embodying my design, both sides of which present substantially the same appearance.

Fig. II represents a plan view of the same, showing only a portion of the tender.

Fig. II-A represents a similar view showing the remainder of the tender; and,

Fig. III represents a rear elevation of the same, the wheels being omitted in this figure for the sake of clarity.

In the present design the principal and dominating features are shown in full lines.

I claim:

The ornamental design for a locomotive as shown and described.

RAYMOND G. F. LOEWY.
